UNITED STATES PATENT OFFICE.

CONYERS BUTTON, OF PHILADELPHIA, PENNSYLVANIA.

DESIGN FOR SCARF.

Specification forming part of Design No. **6,676**, dated May 27, 1873; application filed May 13, 1873.

To all whom it may concern:

Be it known that I, CONYERS BUTTON, of Philadelphia, Pennsylvania, have invented a Design for a Scarf, of which the following is a specification:

In the accompanying drawing, Figures 1 and 2 represent opposite sides of sufficient of a scarf to fully illustrate my design, the remainder of the pattern being merely a repetition of that which appears.

The design consists of a central longitudinal stripe, A, and of three parallel stripes B, C, and D, at each side of the said central stripe; the stripes B C D being arranged closely together, as shown, so that the stripes B and D shall have the appearance of borders or edgings for the intermediate wider stripe C, which is of a

foliated character, so clearly shown in the drawing as to need no minute description. The central stripe A consists of a series of angular projections, *a*, preferably of a variegated shade, arranged upon either side of a central rib, *b*.

Irrespective of the colors employed, I claim—

The design for a scarf, substantially as described, and as represented in and by the accompanying drawing.

In testimony whereof I have signed my name to this specification in the presence of two subscribing witnesses.

CONYERS BUTTON.
